UNITED STATES PATENT OFFICE.

JOSEPH DRIGGOTT, OF CHICAGO, ILLINOIS.

GEM-CLAMPING DEVICE FOR AN ARTICLE OF JEWELRY.

1,182,534.

Specification of Letters Patent.

Patented May 9, 1916.

Application filed December 18, 1915. Serial No. 67,493.

To all whom it may concern:

Be it known that I, JOSEPH DRIGGOTT, a subject of the Czar of Russia, and a resident of the city of Chicago, in the county of Cook and State of Illinois, have invented certain new and useful Improvements in a Gem-Clamping Device for an Article of Jewelry; and I do hereby declare that the following is a full, clear, and exact description thereof, reference being had to the accompanying drawings, and to the letters of reference marked thereon, which form a part of this specification.

This invention relates to improvements in articles of jewelry, such as finger rings, and more particularly to that type of finger rings that are set with single stones or gems, or other ornamental pieces of like character.

Among the objects of my invention is to improve the construction of settings in finger rings of the kind referred to and to provide in particular a clamping device for removably holding a gem or stone in the mounting of the ring.

A clamping device embodying the features of my invention comprises a split or circumferentially contractible, annular clamping member, which has pivotal connection with the ring on the inside thereof, and which clamping member may be swung into and out of clamping engagement with the gem or stone set in said ring for the purpose of permitting said gem or stone to be readily removed from the ring when desired, and be replaced by a stone of the same or different grade and color to meet the wishes of the wearer.

The invention consists further in the matters hereinafter described and more particularly set out in the annexed claims.

In the accompanying drawings: Figure 1 is a side elevational view, with parts in section, of an article of jewelry, such as a finger ring of the type referred to and having applied thereto a clamping device constructed in accordance with my invention, for removably holding the gem or stone in said ring; Fig. 2 is a fragmentary vertical sectional view of the parts shown in Fig. 1, except that the clamping device is shown swung into a position out of clamping engagement with the gem or stone; Fig. 3 is a perspective view on an enlarged scale of my clamping device removed from the ring; and Fig. 4 is a horizontal sectional view taken on line 4—4 of Fig. 1.

In the accompanying drawings, I have shown an article of jewelry, such as a finger ring 10 of that type set with a single stone or gem 11, the latter being removably clamped in the ring by a clamping device embodying the features of my invention. As illustrated, said ring 10 is provided with a "low" setting, that is, the gem or stone 11 is set so that its outer face is substantially flush with the outer face of the ring. Said gem or stone 11 is set in an aperture or hole 12 extending vertically through the front portion or mounting 13 of said ring. Said aperture 12 opens into the inside of the ring, and the outer edge thereof is in the form of an inwardly projecting, overhanging, annular flange 14, against which said stone 11 bears when inserted into said aperture from the inside of said ring. Said gem or stone 11 is inserted into and removed from said aperture 12 from the inside of the ring, and, in order to removably hold said stone in said aperture and against said flange 14, I provide a clamping device 15 of the following construction: As best shown in Fig. 3, said clamping device comprises a split annular clamping member 16 adapted to be inserted into and removed from said aperture 12 from the inside of the ring. Said clamping member 16 is provided with a laterally extending shank or stem 17, the outer or free end of which is secured, by a transversely arranged pivot pin 18, to the ring 10 on the inside thereof. As shown in Figs. 1 and 2, the parts are arranged so that said shank 17 extends to one side of said aperture 12 and is curved longitudinally so as to fit against the inner curved surface of the ring, when said clamping member 16 is swung into the aperture and against the under side of the gem or stone 11 therein. Said ring 10 is also provided in the inner surface thereof with a groove or recess 19 of a length substantially equal to and adapted to receive said shank 17, so that the latter will be flush with the inner surface of the ring, when the clamping member 16 is swung into said aperture 12. As shown, said groove 19 opens at one end into said aperture 12 at the base or inner edge thereof and, furthermore, opens throughout its length into the inside of the ring, so that the shank 17 may be readily and easily swung into and out of said groove.

The clamping member 16 is preferably made of relatively thin, resilient or spring metal, and, being split, may be contracted

circumferentially. The normal or maximum diameter of said clamping member 16 is substantially equal to or slightly greater than the diameter of said aperture 12, and, 5 when swung therein, said clamping member 16, by reason of its contractibility and resiliency, tightly bears against the walls of the aperture and holds the stone 11 therein and against said flange 14. As shown in 10 Figs. 3 and 4, said clamping member 16 is provided adjacent one of its split ends with an outwardly bulged part or boss 20 adapted to snap into a suitable recess or hole 20^a formed in the walls of said aperture 12, 15 and aid in holding the clamping member 16 therein. In order to prevent the clamping member 16 from coming into contact with the inside or lower edge of said aperture when swung therein, the latter is provided 20 with a recess 21 opening into said aperture opposite said groove 19. The walls of said recess are curved transversely and inclined outwardly substantially in an arc of the circle defining the path of swinging movement 25 of the clamping member 16.

The device herein described and shown is used and operated as follows: To place and clamp a stone or gem 11 in said aperture 12, the clamping device 15 is swung 30 into its open or non-clamping position, as shown in Fig. 2. A gem or stone of the proper size is then inserted or dropped into said aperture 12 from the inside of the ring 10, the latter at this time being preferably 35 in an inverted position. The clamping member 16 is then swung into said aperture 12 and against the under side of the gem or stone therein. To remove the stone 11, in case the latter becomes injured or damaged 40 while in the ring, or in case it is desired to replace the stone in use by another one of the same size but of a different value or color as determined by the dictates of the wearer, an inwardly directed pressure is 45 applied against the outer face of the stone. Under such pressure the stone is forced inwardly, and the clamping member 16 swung out of the aperture 12 and into the position shown in Fig. 2. In this position of the 50 parts, the stone may be readily removed or withdrawn from the aperture 12 from the inside of the ring 10, and another stone substituted therefor and clamped in the aperture by swinging the clamping member 16 back into the same.

As shown in Figs. 1 and 3, the outer annular edge 22 of the split clamping member 16 engages the under side of the stone 11, and such edge is preferably beveled or 55 inclined complementary to the inclined under surface of said stone, so that the clamping member will bear properly against the stone and prevent cutting or injuring the same as would be the case if such edge were 60 a sharp one.

The advantages arising from the use of my device reside in the fact that a stone or gem may be readily removed from a ring in case it is desired to replace a damaged or broken stone, or substitute for the stone 70 in use a stone or gem of substantially the same size, but of a character different in color or value from the one in use. Furthermore, the clamping device having pivotal connection with the ring is always connected with the ring whether in clamping or in non-clamping position, and therefore it is not necessary to completely remove the clamping device from the ring when it is desired to remove a stone therefrom. Moreover, said clamping device having pivotal connection with the ring, the stone may be 75 set and removed without requiring the aid of a jeweler or other expert, as no tools of any kind are necessary to insert or remove 80 a stone from the ring. Then again, my clamping device is simple in its construction and operation, and is inexpensive to make and install in a ring. With a ring provided with my clamping device, a series of 85 stones or gems of different colors may be used with the same ring, and thereby enable the wearer to readily and easily set in the ring any one of the stones whenever desired. 90

In the drawings I have shown my device as being applied to a finger ring, but it is of course to be understood that my device may be equally as well applied to any other piece of jewelry for the purpose of clamping 100 a stone or gem in the setting thereof. 95

Although I have described and shown herein in detail one form of clamping device embodying the features of my invention, yet it is to be understood that the details of construction and arrangement of parts shown and described may be variously changed and modified without departing from the spirit and scope of my invention, and I do not wish to be limited and confined to the particular details of construction and arrangement of parts illustrated, 110 except as hereinafter claimed. 115

I claim as my invention:

1. The combination with an article of jewelry having a gem or stone receiving opening, the latter having a side wall and provided at one end with an inwardly extending part, of a clamping device for removably holding the gem or stone in said opening and comprising a contractible clamping member adapted to be inserted in said opening, engage the side wall thereof beneath the gem or stone, and hold the latter against said inwardly extending part, and means for pivotally connecting said clamping member with said article of jewelry, so that said clamping member may be swung into and out of said opening. 125

2. The combination with an article of jew- 130

elry having a gem or stone receiving opening, the latter having a side wall and provided at one end with an inwardly extending part, of a clamping device for removably holding the gem or stone in said opening and comprising a contractible clamping member adapted to be inserted in said opening, engage the side wall thereof beneath the gem or stone, and hold the latter against said inwardly extending part, and said clamping member being provided with a shank having pivotal connection with said article of jewelry, so that said clamping member may be swung into and out of said opening.

3. The combination with an article of jewelry having a gem or stone receiving opening, the latter having a side wall and provided at one end with an inwardly extending part, of a clamping device for removably holding the gem or stone in said opening and comprising a contractible clamping member adapted to be inserted in said opening, engage the side wall thereof beneath the gem or stone, and hold the latter against said inwardly extending part, said clamping member being provided with a laterally extending shank having pivotal connection with said article of jewelry, so that said clamping member may be swung into and out of said opening, and said article of jewelry being provided at one side of said opening with a groove adapted to receive said shank.

4. The combination with an article of jewelry having a gem or stone receiving opening, the latter having a side wall and provided at one end with an inwardly extend-

ing part, of a clamping device for removably holding the gem or stone in said opening and comprising a contractible clamping member adapted to be inserted in said opening, engage the side wall thereof beneath the gem or stone, and hold the latter against said inwardly extending part, said side wall being provided with a recess, said clamping member being provided with a boss or projection adapted to enter said recess, and means for pivotally connecting said clamping member with said article of jewelry, so that said clamping member may be swung into and out of said opening.

5. The combination with an article of jewelry having a gem or stone receiving opening, the latter having a side wall and provided at one end with an inwardly projecting annular flange, of a clamping device for removably holding the gem or stone in said opening and comprising a circumferentially contractible clamping member adapted to be inserted into said opening, engage the side wall thereof beneath the gem or stone, and hold the same against said flange, and said clamping member being provided with a laterally extending shank having pivotal connection with said article of jewelry, so that said clamping member may be swung into and out of said opening.

In testimony, that I claim the foregoing as my invention, I affix my signature in the presence of two witnesses, this 15th day of December A. D. 1915.

JOSEPH DRIGGOTT.
